MATCHBOOK HOLDER

Alfred S. Bodin, 7510 W. 109th St., Worth, Ill.

Filed Dec. 15, 1955, Ser. No. 553,229

5 Claims. (Cl. 206—31)

The present invention relates to certain new and useful improvements in a matchbook holder, that is, a specially constructed device which isolates and keeps the book of safety matches in a readily accessible position for severance and positions the usual abrasive strip apart from the matches, thus minimizing accident.

A specific purpose of the invention is to provide a simple, practical, economical and easy-to-use matchbook holder, which will serve to provide a specific place for matchbooks with the stated safety feature added, whereby to thus provide a novel and highly useful adaptation primarily for home use.

As will be hereinafter more particularly evident, the inventive concept, in an over-all sense, is susceptible of satisfactory accomplishment in more than one structural embodiment. In the instant presentation two embodiments are disclosed, generically construed the invention has to do with a holder comprising a substantially rigid body of suitable structural form and which is characterized by means to receive and temporarily store the cover of the matchbook in an out-of-the-way position, complementary means functions to expose and maintain the book of matches in a position set apart from the cover and in unobstructed readiness for handy severance and detachment one by one. The last named means embodies a protective shield which is of an area greater than the full book of matches. Therefore, the matches are susceptible of accessible maintenance on one side and within the marginal limits of the shield and this same shield has a prescribed match slot or opening with which the abrasive strip is aligned and exposed, the slot being accessible for use only from the other side of the shield.

More specifically, in one form or embodiment of the invention the body means takes the form of a flat panel and this is provided intermediate its ends or at its median portion with a slot which may be said to provide the panel into upper and lower half portions. The upper half portion constitutes the aforementioned protective shield while the lower half portion serves to accommodate the front and back portions of the book cover in a folded state. Specifically designed means is carried by the median portion of the panel on one side thereof and in alignment with the slot and this is constructed to pocket, anchor and hold the stub of the book after the cover has been freed from the staple, with the matches cooperating with the stated one side of the shield and with the abrasive strip in exposed and accessible alignment with the stated slot.

In the other form of the invention a hollow box-like receiver is formed at one end of the body means and is also provided interiorly with a pair of cooperating rollers which catch hold of and draw the matchbook cover in a lengthwise manner through a slot in the receiver and between the rollers, whereby it is stored within the compartment or space of the receiver. At the upper end of the receiver there is an extending flat panel and here again this constitutes the protective shield and is provided with

2

a slot which is properly located so that when the matchbook is positioned in its final and intended locale, the abrasive strip lines up with the slot.

Admittedly, the art to which the invention relates shows that many and varied styles and forms of holders have been made and appropriated for use with the idea of safety in mind. It follows that it is an object of the present invention to structurally, functionally and otherwise improve upon similarly constructed and performing matchbook holders and, in doing so, to provide handy and practical means in which manufacturers will find manufacturing and retailing problems suitably solved and users will find their anticipated needs aptly met.

Other objects, features and advantages will become subsequently apparent from the following description and the accompanying sheets of illustrative drawings.

In the drawings, wherein like numerals are employed to designate like parts throughout the views:

Figure 1 is a perspective view of a matchbook holder constructed in accordance with the principles of the invention and showing the same in readiness for use with the matches on what may be called the front side;

Figure 2 is a perspective view of the same observing the opposite or rear side;

Figure 3 is a fragmentary section showing the initial step in inserting the tip of the matchbook cover;

Figure 4 is a similar fragmentary section showing the next step;

Figure 5 is a succeeding fragmentary sectional view showing the step wherein the cover is wedged loose from the usual staples at the stub of the book of matches;

Figure 6 is a view in section showing the complete holder and the final step with the matches on one side and the abrasive accessible from the other side;

Figure 7 is a top plan view with portions broken away and shown in section and with the matches omitted;

Figure 8 is a section on the line 8—8 of Figure 6 looking in the direction of the arrows;

Figure 9 is a perspective view of a simplified form of the invention, the modification hereinbefore touched upon;

Figure 10 is a perspective view of the same observing the rear side with the abrasive visible for use;

Figure 11 is a vertical section on the line 11—11 of Figure 10 looking in the direction of the arrows; and

Figures 12 and 13 are cross-sections on the horizontal lines 12—12 and 13—13, respectively, of Figure 11.

Referring first to the embodiment of the invention appearing in Figs. 1 to 8 inclusive it will be seen that the body means is preferably of one-piece construction. It may be of any appropriate lightweight rigid material. The aforementioned box-like receiver is denoted by the numeral 16 and it has upper and lower end portions. It is closed except at the top and it is here provided to one side of the vertical center with an upstanding extension which is described as a flat faced substantially rectangular panel 18. The front face of the panel is denoted at 20 while the rear face is denoted at 22. At the intermediate upper portion there is a horizontal abutment 24 which is suitably beveled to perform in a manner to be described. Just above the top of the receiver and below said abutment the panel is provided with a substantially rectangular abrasive accommodation and exposing slot 26. The marginal edges of this slot are preferably beveled in the manner shown. To the left of the panel the upper portion of the receiver is fashioned into a relatively thick embossment 28 which in cross-section may be described as a rib and this has a convex surface 30 which functions as a wedge. This embossment is recessed to provide a pocket 32 the bottom of which constitutes a stop shoulder 34. The numeral 36 designates a passage into the receiver. The recess constitutes a

holding pocket for the stub portion 38 of the matchbook. The slotted panel 18 constitutes a shield. On the interior of the receiver 16 are two spaced parallel rollers, one to the right of the passage 36 and mounted for idling and denoted by the numeral 40 (see Fig. 8). The companion roller 42 is to the left of the passage and both rollers are rubber covered and the roller 42 is provided with spurs, if desired. It will be seen in Fig. 8 that the roller 42 has an extension 44 passing through the side wall of the receiver where it is provided with a finger gripping and roller turning knob 46.

It is believed that by considering Fig. 1 and then Fig. 2, the position of the matches in the holder and the locations of the abrasive strip will be clear. However, and in order to accomplish this reference should be made to Fig. 3. Here the tip 48 of the front portion 50 of the matchbook is inserted and passed downwardly through the pocket 32 and then through the passage where it is grasped between the rollers 40 and 42. This places the book of matches 52 in the approximate position shown. Obviously by catching hold of the knob and turning the roller 42 clockwise the roller 40 rotates in an opposite direction and the two rollers feed the cover downwardly into the receptacle or space of the receiver 16. Referring to Fig. 4 it will be seen that the position is such that the back portion of the cover 54 now parallels the front side 20 of the shield 18 and that the stub 38 is now in contact indirectly with the horizontal abutment 24. Continued turning of the rollers in the same direction now starts the book of matches to reverse (Fig. 5) and next the cover portions are drawn down between the rollers until that portion of the cover denoted at 54 is ripped loose and freed from the usual wire staple 56. Continued operation of the rollers draws the cover into the receiver and the book of matches is flipped up against the abutment 24 to assume the final position depicted in Fig. 6. In this position the stub 38 has been forced and is squeezed down into the pocket 32 where it comes to rest against the shoulder 34 and at the same time the abrasive strip 58 is brought into registry with the slot 26 where it is now accessible for use.

In the simpler form of the invention seen in Figs. 9 to 13 inclusive the body means is denoted by the numeral 60. This, specifically, is a rectangular rigid panel. The median portion of the panel is provided with a beveled-edge horizontal slot 62 which may be said to divide the panel into an upper half portion 64 and a lower half portion 66. The upper half portion constitutes the safety shield for the matches. On the opposite or front side of the panel, the side 68 in Fig. 11, there is the desired abutment 70 and below this is an integral enlargement or embossment which is denoted by the numeral 72. This is of rib-like cross-section. It is provided with a recess 74 functioning as a pocket and having a shoulder 76 at the bottom serving as a stop. If desired there may also be a slot as at 78. Although it is not absolutely essential it is desirable here to provide a plate as at 80 which is described as a cover and has marginal flanges 82 and is hingedly mounted at its bottom at 84. The upper swingable edge is provided with a finger-piece 86.

Although the rollers shown in the first described form of the invention are not used here it will be evident that the provision of the hinged cover or lid 80 permits the lower half portion 66 in the cover to function as a receiver and to provide space therein for the flaps or front and rear portions of the match holder. It is believed that here the portions of the match holder may be satisfactorily referred to by the same numerals already utilized in connection with the description of Figures 1 to 8 inclusive. In the form of the invention under consideration the omission of the wedge means 30 and the rollers makes it necessary for the user himself to catch hold of and pull the cover loose from the staple. After the free end of the cover is inserted into the pocket 74 and the tip is passed down through the slot 78 and, when accessible for grasping, it is pulled down until the stub 38 of the

book matches is firmly wedged and seated in the pocketing recess or cavity 74 with the fingers replacing the rollers of Figures 1-8 as the pulling means. The lower half of the cover is then firmly creased and the tip end pointed back upward and inserted in the slot 78 below the pocket. It is not torn away since it must serve the purpose of removal of the stub when the matches have been used up. The lower half portion of the cover is removed from the slot at its tip end and the upper half of the cover is pushed upward with a sidewise motion until the stub is free and the entire used package is removed in the reversed action.

Although the lid or cover 80 is not essential it is believed to be desirable in that it may be used to contain advertisements. It also finishes off the appearance of the holder to a greater degree and provides a generous space for ads on front and reverse sides. It also covers any ads that may appear, as usual on the book matches themselves.

An advertiser using this medium need only make a single investment in the holder and it will keep his message permanently displayed, as is obvious. It is designed to attract the attention of observers by its own ingenious appearance and mode of use.

Briefly the steps involved in using this form of the invention consists in loosening the cover and positioning the same with the flaps or portions as illustrated in Fig. 11 with the matches seated in the pocket and in readiness for use in an obvious manner. No wedge action is necessary here since the user will do the separating himself by hand. After this is done, the free end of cover is inserted in pocket and when accessible for grasping at underside of pocket, it is pulled down until stub of book matches is firmly wedged and seated in the existing pocket. The stripping of the stub may also be accomplished by pulling downwardly on the cover after the cover is inserted into the pocket. The lower half of cover is then firmly creased (as shown) and tip end pointed back upward and inserted in slotted opening below pocket. It is not torn away since it must serve the purpose of removal of stub when matches have been dissipated. The lower half of cover is removed from the slot at its tip end and upper half of cover is pushed upwardly with a sidewise motion till stub is free and entire affair is removed in reverse action. The abrasive or media or strip comes into registry with the slot means 62 as shown in Fig. 10 and the device is ready for use. Since many users fail to close the cover on a book of matches they are apt to encounter, as most have done, an accident resulting in burns.

It is to be noted that the safety feature is automatic by simply flipping Fig. 9 over to reverse side in hand. It is positive without giving it thought. It is taken care of in the process of striking match.

The device may be constructed and used as shown in its respective modification in the figures of the drawings. Or, the form seen in Figures 9 to 12 may have a nail hole at the top and be hung up on a suitable supporting surface in the home when not in use. It is also desirable in many instances to attach the form of the invention seen in Figs. 1 to 8 inclusive to a baseboard (not shown) which is screwed or otherwise nailed to the wall and to provide a hinge connection between the holder and the baseboard so that practical usage may be promoted. Under this arrangement a specific place for book matches is provided and the matches may be hung high and away from the reach of children.

It is to be stated that the rib or embossment 72 as seen in Fig. 11 may be provided on its bottom with a detent and that the grip 86 may be resilient to keep the cover 80 closed. Also in both forms of the invention a clearance notch 88 may be provided for the accommodation of the wire staple means 56.

The foregoing is considered as illustrative only of the principles of the invention. Further, since numerous modifications and changes will readily occur to those

skilled in the art, it is not desired to limit the invention to the exact construction and operation shown and described, and accordingly, all suitable modifications and equivalents may be resorted to, falling within the scope of the invention as claimed.

What is claimed as new is as follows:

1. A match book holder comprising a substantially flat panel provided at its median portion with a slot dividing said panel into upper and lower half-portions, the upper half-portion constituting a protective shield, the lower half-portion being at least equal in area to the upper half-portion and serving to accommodate the front and back portions of the book cover, and means carried by said median portion, located on one side thereof and in alignment with said slot for pocketing, anchoring and holding the stripped stub of said book with the matches cooperating with the stated one side of said shield and the abrasive strip in exposed and accessible alignment with said slot.

2. The structure defined in claim 1 and wherein said means comprises an outstanding embossment recessed and providing a pocket for retentive reception of said stub.

3. The structure defined in claim 2 and wherein said lower portion is provided with an outwardly and downwardly swingable cover which, when closed, parallels said lower portion and provides a storage receiver for the confinable portions of said match book cover.

4. A match book holder comprising a hollow box-like receiver having top and bottom portions, and provided at its top portion with an entrance slot and a communicating stub containing and retaining pocket, roller means operatively mounted in said receiver in cooperating relation in respect to said slot, and complemental means to expose and maintain the book of matches in position set apart from the cover and in unobstructed readiness for severance and detachment, said last named means em-

bodying a protective shield of an area greater than the full book of matches whereby the matches are susceptible of accessible maintenance on one side within the marginal limits of said shield, and said shield having a prescribed match slot with which the abrasive strip is aligned and exposed, said slot being accessible for use only from the other side of said shield.

5. A match book holder comprising a panel having a slot, a hollow box-like receiver at one end of the panel with feed rollers therein, means for holding the book of matches and threading the cover thereof between the rollers and into the space of the receiver, said means being positioned opposite said slot, and means on the exterior of said receiver for handily operating said rollers, said holding means functioning to expose and maintain the book of matches in a position set apart from the cover and in unobstructed readiness for severance and detachment behind said panel, the latter constituting a protective shield of an area greater than the full book of matches whereby the matches are susceptible of accessible maintenance on one side within the marginal limits of said shield, and said shield having a prescribed match slot with which the abrasive strip is aligned and exposed, said slot being accessible for use only from the other side of said shield.
